CENTRALIZED OILING SYSTEM

Ernest W. Davis, Oak Park, Ill., assignor to Gits Bros. Mfg. Co., Chicago, Ill., a corporation of Illinois

Application October 20, 1949, Serial No. 122,543.

4 Claims. (CL 184—7)

1

My invention relates to centralized oiling systems, and its general object is to provide an efficient oiling system that can be manufactured at low cost. A more specific object is to devise a centralized oiling system having an oil line containing measuring valves, and provided with a centralized pumping unit having an improved timing mechanism for alternately applying a predetermined pressure to the oil line and then releasing said pressure at predetermined time intervals.

An embodiment of my invention is illustrated in the accompanying drawing, in which the central pumping unit 2 is shown in sectional elevation. The oil reservoir 4, is provided with a cover 6. The piston 8 of the pump 9 reciprocates vertically within the cylinder portion 10, when the cam 12 is rotated by the electric motor 14. The cam 12 moves the piston 8 downwardly by engagement with the cam wiper 16, and the spring 18 moves the piston 8 upwardly by engagement with the collar 20. When the piston 8 occupies its highest position, it uncovers the port 22; so that oil from the reservoir 4 may flow into the cylinder 10. Then when the piston 8 is moved downwardly, it first covers the port 22, and then forces oil from the cylinder 10, past the check valve 24, through the discharge port 26, and into the oil line 28. The oil line 28 delivers oil under pressure to a plurality of measuring valves 30, 32, and 34, for supplying measured quantities of oil to the bearings 36, 38, and 40, respectively, of the machine to be lubricated. These measuring valves are of a type that passes a measured quantity of oil at each application of oil pressure in the oil line, succeeding a release of the pressure therein. Measuring valves of this character are well known to those skilled in the lubricating art, and therefore further description seems unnecessary.

The riser tube 42 connects with the discharge port 26, and is provided at its upper end with a close fitting plunger 44, which is vertically movable between its uppermost position, as shown by full lines, and its lowermost position, as shown by dotted lines. The plunger 44, while occupying its lowest position, closes the opening 46, thereby providing a by-pass valve, which forms an important element in the invention, and which is identified in general by the numeral 48. The upper end of the plunger 44 is provided with a head 47, which limits downward movement of the plunger 44 by engagement with the upper end of the riser tube 42. When the by-pass valve 48 is open, it allows oil to flow from the riser tube 42, through the by-pass conduit 50, and

2

into the tilting bucket 52. The tilting bucket 52 is pivoted on the horizontal shaft 54, which is supported by the reservoir 4.

The tilting bucket 52 is free to oscillate between the upper position, as shown by full lines, and the lower position, as shown by dotted lines, and is so constructed and arranged that it will remain in the upper position when it is empty, and will be moved by gravity to the lower position when a sufficient quantity of oil flows therein from the by-pass conduit 50. It will be observed that when the tilting bucket 52 moves from the upper position to the lower position, the connecting structure 56 then urges the plunger 44 downwardly so as to close the by-pass valve 48. It will also be observed that when the tilting bucket 52 occupies its lower position, sufficient pressure in the riser tube 42 will cause the plunger 44 to move upwardly, thereby restoring the tilting bucket 52 to its upper position. By means of this co-action, the tilting bucket 52 actuates the by-pass valve 48, and the by-pass valve 48 actuates the tilting bucket 52. The reciprocal effect thus attained is utilized with particular advantage in carrying out the objects of the invention, as will appear hereinafter.

Operation

The electric motor 14 is shunted across the motor that operates the machine to be lubricated, so that the motor 14 will drive the pump 9 whenever the machine is running and at no other time. Operation of the pump 9 builds up oil pressure in the oil line 28, and thereby causes each of the measuring valves 30, 32, and 34 to discharge a measured quantity of oil. During this operation of the measuring valves, the tilting bucket 52 will occupy its lower position, as shown by the dotted lines, and the by-pass valve 48 will be held closed. When the tilting bucket 52 is moved to its lower position, the oil contained therein will flow out by gravity, and will return to the oil in the reservoir 4 to be pumped over again.

After all the measuring valves have operated, the continued operation of the pump 9 will increase the oil pressure in the riser tube 42 until it is sufficient to move the plunger 44 upwardly, thereby returning the tilting bucket 52 to its upper position, and thereby opening the by-pass valve 48. This releases the pressure in the oil line 28, so that the measuring valves 30, 32, and 34 may restore to normal loading position in the manner well known to those skilled in the art. Opening of the by-pass valve 48 also allows oil discharged by the pump 9 to flow through the by-

pass conduit 50 and discharge into the tilting bucket 52. After sufficient oil has discharged into the tilting bucket 52, the center of gravity of the bucket (including the oil therein) will be shifted to a position at the right of the shaft 54, whereupon the tilting bucket 52 will swing down to its lower position, and the by-pass valve 48 will be closed by this action, thereby completing the cycle of operation.

In order to secure uniform and satisfactory operation, it is desirable that the oil level in the reservoir 4 shall be no higher than the lowermost portion of the tilting bucket 52 while in its lower position. In the preferred embodiment of this invention, the capacity of the tilting bucket 52 is substantially greater than the combined discharge capacities of all the measuring valves in the oil line 28. It is to be understood that in the particular embodiment of this invention, as herein shown and described, certain departures from commercial design have been purposely employed in order to make the drawings more understandable. Many modifications and improvements in this construction could be made by those skilled in the art without departing from the spirit of the invention.

I claim:

1. In a centralized oiling system having an oil reservoir for supplying oil to a power-driven pump arranged to discharge said oil under pressure into an oil line to which is connected a plurality of measuring valves; a by-pass valve for by-passing oil from said oil line, said by-pass valve being movable to an open position and a closed position, and said by-pass valve including a cylinder portion connected with said oil line, and a plunger portion exposed to said oil pressure and reciprocable in said cylinder portion, and said by-pass valve having a port therein, and said plunger portion being movable to positions that open and close said port; and an unbalanced tilting bucket oscillatable about a substantially horizontal axis to an upper position and a lower position, said tilting bucket being shaped to retain a substantial quantity of oil while occupying said upper position and to discharge said oil when moved to said lower position; and a by-pass conduit for conducting said by-passed oil from said by-pass valve to said tilting bucket, said tilting bucket being moved to said lower position by the force of gravity acting on the combined mass of said tilting bucket and said by-passed oil contained therein, and said tilting bucket being operatively connected with said plunger portion, and said plunger portion being moved to a position covering said port when said tilting bucket is moved to said lower position, and said plunger being moved to a position that uncovers said port when the oil pressure in said oil line reaches a predetermined value, and said tilting bucket being moved to said upper position by said uncovering movement of said plunger.

2. In a centralized oiling system having an oil reservoir for supplying oil to a power-driven pump arranged to discharge said oil under pressure into an oil line to which is connected a plurality of measuring valves; a pressure-opened by-pass valve connected with said oil line for

releasing the oil pressure therein when said pressure reaches a predetermined value; oil actuated timing mechanism receiving oil discharged through said by-pass valve, said timing mechanism being movable from a first position to a second position and movable from said second position back to said first position, and said timing mechanism being moved from said first position to said second position in response to the delivery thereto of a predetermined amount of oil from said by-pass valve; and connecting structure between said by-pass valve and said timing mechanism, said connecting structure transmitting motion from said by-pass valve to said timing mechanism in a direction to move said timing mechanism to said first position when said by-pass valve is opened, and said connecting structure transmitting motion from said timing mechanism to said by-pass valve in a direction that closes said by-pass valve when said timing mechanism is moved to said second position.

3. In a centralized oiling system having an oil reservoir for supplying oil to a power-driven pump arranged to discharge said oil under pressure into an oil line to which is connected a plurality of measuring valves; a pressure-opened by-pass valve connected with said oil line and responsive to the oil pressure therein for releasing oil from said oil line when the pressure therein reaches a predetermined value; and gravity-actuated timing mechanism receiving oil discharged through said by-pass valve and responsive to the accumulation of a predetermined weight of said received oil for closing said by-pass valve.

4. In a centralized oiling system having an oil reservoir for supplying oil to a power-driven pump arranged to discharge said oil under pressure into an oil line to which is connected a plurality of measuring valves; a pressure-opened by-pass valve connected with said oil line and responsive to a predetermined pressure therein for releasing oil from said oil line; gravity-actuated timing mechanism receiving oil discharged through said by-pass valve and responsive to the accumulation of a predetermined weight of said received oil for closing said by-pass valve; and leverage structure between said by-pass valve and said timing mechanism for transmitting motion from said timing mechanism to said by-pass valve and for transmitting motion from said by-pass valve to said timing mechanism, said leverage structure providing a lever of the second class during first motion transmission, and said leverage structure providing a lever of the third class during said second transmission.
